ADJUSTABLE PATTERN

Henry B. Donning, New Rochelle, N. Y.

Application June 30, 1939, Serial No. 282,050

3 Claims. (Cl. 33—12)

This invention relates to garment patterns, and particularly to the provision of patterns having the means for alining associated pattern pieces upon a fabric for the matching of the resulting fabric pieces cut from the patterns to produce neat and finished appearances in the resulting garment, or garment parts; and the object of the invention is to provide predetermined characterized sections, preferably of an irregular contour, on associated garment patterns to facilitate matching of the fabric pieces cut from associated patterns by the removal of the characterized section of one pattern piece and marking the same to aline it with the fabric from which such pattern piece is cut, and then in placing the removed characterized section of one of the first mentioned pattern pieces upon the associated pattern piece to mark the latter for proper alinement on the fabric from which the outline of the second mentioned pattern piece will be cut; a further object being to arrange the characterized and removable sections on the associated pattern pieces in a definite relationship with respect to one end of the pattern piece to provide proper alinement or matching of the resulting garment pieces, and also in so arranging these sections on the pattern pieces as to not interfere with the variations in length of the garment pieces cut from said patterns; a further object being to provide a novel method of cutting garment pieces from patterns of the character described as more fully hereinafter set forth; and with these and other objects in view, the invention consists in a pattern of the character described which is produced in accordance with the method more fully hereinafter set forth.

The invention is fully disclosed in the following specification, of which the accompanying drawing forms a part, in which the separate parts of my improvement are designated by suitable reference characters in each of the views, and in which:

Fig. 1 is a diagrammatic illustration of an elongated pattern strip showing the general arrangement of parts of a garment thereon, and illustrating my invention.

Fig. 2 is a perspective view showing one end portion of the pattern sheet arranged upon a fabric illustrating the method of marking the removable alinement gage section thereof; and,

Fig. 3 is a view similar to Fig. 2 showing the next adjacent portion of the pattern strip illustrating the method of marking the adjacent associated pattern from the removable gage of the pattern illustrated in Fig. 2.

To illustrate one adaptation of my invention, I have shown in Fig. 1 of the drawing diagrammatically, leaving out all incidental detail features, an elongated pattern strip upon which is arranged part of the patterns of a garment. 5 This illustration is in accordance with the teachings in a prior application, Ser. No. 240,445, filed November 15, 1938. In other words, in the present illustration, the invention is applied to a pattern wherein all of the pattern pieces of a complete garment are laid out upon an elongated pattern strip to facilitate the proper cutting of the various pattern pieces from the fabric, and to minimize as much as possible the amount 10 of material required in cutting all of the garment pieces by a close arrangement of the patterns upon the strip. However, in cutting patterns of the character under consideration, or in fact in cutting garment pieces from any type and kind 15 of pattern, it has been difficult to provide a proper matching of the separate garment pieces in associated pieces of one part of a garment, so as to produce a neat and finished appearance. This is especially true in dealing with such fabrics as plaids. It is the purpose of my invention to provide a simple and yet effective means for 20 eliminating these difficulties, thus making it possible for the dressmaker to cut out associated garment pieces with the assurance of having the 25 stripe of a plaid match at least in one direction on the garment. This will enable the dressmaker to produce neater and more finished effects in the resulting garment.

In Fig. 1 of the drawing 10 represents an 30 elongated pattern strip, or at least part of a strip of this kind, and on this strip is diagrammatically illustrated parts of the patterns of a complete garment, which are designated by the legends—"Sleeve, Center back, Center front 35 —B—; Center front —S—, Shoulder pad, Back neck facing, Side front, Sleeve facing, Panel facing, Placket, Center front skirt, Side front skirt, Center front facing, and Back skirt." A number 40 of the pattern pieces identified as above are provided with sections 11, which in the present 45 illustration are of triangular contour, it being understood, however, that any other desired contour may be provided, preferably of a geometric lay-out, so that no possible confusion could exist 50 in the laying of the section of one pattern piece upon the section of an associate pattern piece, as will hereinafter more clearly appear.

To illustrate the invention and the method of procedure, I have shown in Figs. 2 and 3 of the 55 drawing, the associated pattern pieces designated

by the legend "Side front skirt," which will be identified by the reference character 13, and the "Back skirt" identified by the reference character 12. These pattern pieces 12 and 13 include other markings which are essential for the use thereof in the outlining of a garment. However, to simplify the present illustration and avoid confusion many of these markings are omitted in the illustrations in Figs. 2 and 3 of the drawing except the representations 14, 14a, which consist in transverse lines designating the hip lines of the pattern pieces. At 15, 15a, are shown other markings where the patterns may be cut in the lengthening or shortening of the pattern pieces in accordance with the teachings in my prior application above referred to.

In arranging the gage sections 11 upon the pattern pieces 12, 13, they are arranged in a definite relationship with respect to the hip lines 14, 14a, it being understood that the hip lines in question have an identical arrangement on the two associated pattern pieces 12 and 13. In other words, when the two associated pattern pieces or the garment pieces cut therefrom are arranged one upon the other, the hip lines 14, 14a will register.

In carrying out the method, the pattern strip 10 is laid upon the folded plaid fabric 16 which is folded as seen at 17. The strip 10 extends longitudinally of the folded fabric as will be apparent. The section 11 of the pattern piece 12 is then cut out to form the triangular piece 11a shown in the extended position in Fig. 2 of the drawing, and when removed, the pattern piece 12 is marked by the cross lines 18 to register with the cross lines 19 of the plaid of the fabric, after which the removed piece 11a is again placed into position on the pattern piece 12 and the lines 18 are extended across the piece 11a as indicated at 18a in Fig. 2. The gage piece 11a is then arranged in a triangular recess 20 formed by removing the gage 11 of the pattern piece 13. The gage piece 11a is shown in position in Fig. 3, and the markings 18a are extended onto the pattern piece 13 as seen at 18b, after which the gage piece 11a is removed, and the sheet 10 is then shifted longitudinally of the fabric 16 to align the markings 18b with the adjacent cross lines or markings in the plaid of the fabric 16, which, for example, might constitute the markings 19a.

In connection with the foregoing, it will be understood that it is preferred that the respective pattern representations on the sheet 10 be cut one at a time from one end of the sheet so that no difficulty will be experienced in matching the respective patterns with the cross markings of the plaid of the fabric in the manner illustrated above. However, after the "Back skirt" and "Center front facing" have been cut from the fabric and proper alinement of the "Side front skirt" has been made, including the "Center front skirt," then the pattern pieces may be cut up to and including the "Panel facing." Thereafter the adjustment of the "Side front" is made as well as the adjustment of the "Center front S," after which all of the pattern pieces may be cut out up to the "Shoulder pad," etc., throughout the full length of the elongated pattern strip.

Another method which could be followed would be to cut out each of the pattern representations and then lay each piece upon the fabric following the lay-out of an instruction diagram, alining each pattern piece on the plaid of the fabric before cutting the same.

It will also be understood that the same pro-

cedure is followed in cutting out the gage sections 11 of other associated pattern pieces; that is to say, the gage 11a is only used upon the associated skirt part 13. The other associated garment parts will be correspondingly dealt with.

Care will of course be taken to make the necessary adjustment in each pattern piece with respect to lengths before the pattern pieces are cut from the fabric. In laying out the gage sections 10 11 on the pattern pieces, they will be so arranged thereon as to not interfere with the length adjustment portions of the respective patterns. Otherwise, the particular location of these gage sections is immaterial, except that they be identical on the associated parts, so that, for example, in assembling the parts of a skirt, the horizontal lines of a plaid will be in common alinement circumferentially of the skirt, thus producing a neat and finished appearance.

20 In some instances, it may also be possible to align garment parts on the longitudinal lines of the plaid, but this as a general procedure cannot be followed or adhered to. However, where it is possible to do so without effecting a waste of material, or to otherwise disturb the lay-out of patterns on the fabric, this procedure can be followed. In such instances, the longitudinal lines will also be arranged upon the gage sections 11 and transferred to the associated pattern pieces 30 similar to the lines 18, 18a, and 18b.

It will of course be apparent that the principles of my invention are applicable to patterns of any type and kind for use in conjunction with checked, plaid or other type and kind of characterized cloth, and may be used in connection with designed fabrics of any type and kind. The markings as at 18, 18a, 18b, are consistent with the type and kind of characters employed upon the fabric.

40 It will of course be understood that while all of the gage sections 11 as applied to the different garment pieces, have been shown as being of the same contour, these sections need only be of the same contour and size on associated garment parts, and may be varied as to size on other associated garment parts, and in fact, varied as to contour.

Having fully described my invention, what I claim as new and desire to secure by Letters 50 Patent, is:

1. In a garment pattern, a gage section of irregular outline, said section being arranged at a predetermined distance from one end of the pattern, said gage section being removable from the pattern sheet to form an opening in the pattern to render the design of a fabric upon which the pattern is laid for cutting visible through said opening, and the opening together with said gage section facilitating proper alinement of the pattern with the design of the fabric.

2. An elongated pattern strip having a series of garment pattern pieces arranged longitudinally thereof, predetermined associated pattern pieces having markings thereon at equal distances from corresponding ends thereof, said markings defining removable sections of similar irregular contour on said associated pattern pieces, and said removable sections comprising interchangeable gage means adapted for the recording of points of alinement between a fabric design and one of said associated pattern pieces and subsequent transferring of said points of alinement to another of said associated pattern pieces thereby facilitating proper alinement of the fabric therewith.

3. In a pattern of the class described, associated pattern pieces for use in forming associated parts of a garment, said pattern pieces having markings thereon defining gage sections of similar irregular contour positioned at predetermined like distances from corresponding ends of

said pattern pieces, and said gage sections being removable and interchangeable on the respective pattern pieces in alining one pattern piece on a characterized fabric to match the lay out of the other pattern piece of the same fabric.

HENRY B. DONNING.
